 graphie m. b. H., Berlin, Germany, a corpora-
 tion of Germany

Application March 2, 1935, Serial No. 8,969
 In Germany February 1, 1934

5 Claims. (Cl. 179—1)

This invention is concerned with an amplifier with mains-connection means in combination with a microphone. According to this invention, the operating current for the microphone is derived from a rectifier by way of a filter or smoothing means, the capacities of the latter consisting of electrolytic rectifiers.

This invention shall be explained in more detail by reference to the accompanying drawing. The amplifier comprises the two multi-grid type tubes 1 and 2, for which the working potentials are derived from alternating current mains by way of the main switch 3 and the primary winding 3a of transformer 4. The heating current for the tubes is taken from the winding 5, and the plate potential from the winding 6 through the rectifier tube 7 and the low-pass filter 8.

According to this invention, the operating D. C. for the microphone 9 is derived from the winding 10 of the mains-connected transformer by way of the rectifier 11 and the low-pass filter 12. The rectifier 11 is preferably of the so-called "dry" kind, say, a selenium or a cuprous-oxide rectifier. The shunt capacities of the filter chain 12 consist of electrolytic condensers. It has been ascertained that a size of 100 mfd. each suffices to insure adequate smoothing of the rectified voltage to be supplied to the microphone, so that disturbing (background) noises will not be perceptible in the amplified microphone currents. The advantage of an arrangement as here disclosed consists in that by the use of electrolytic condensers the operating direct current can be derived in a simple manner from the power pack without the construction of the outfit becoming particularly costly or cumbersome.

Contrasted with battery voltage supply for the microphone, say, by the use of a dry battery or cell, the present arrangement offers the advantage that the microphone when the outfit is connected, is ready for operation at any time while, on the contrary, when the outfit is disconnected, no unnecessary consumption of current takes place.

Failure of the outfit on account of exhaustion of the microphone battery source is here, of course, impossible.

I claim:

1. An amplifier circuit having connected therewith a microphone operated by current means energized from an alternating current source, said operating current means comprising a source of alternating current, a single transformer having a primary and a plurality of secondary windings, the primary winding of said transformer connected to the alternating current source, one of

the secondary windings of said transformer connected to a rectifier tube, a filter connected to said rectifier tube and said secondary winding, said filter connected to said amplifier for supplying current thereto, at least one other secondary winding of said transformer connected to a copper oxide rectifier, a second filter connected to said copper oxide rectifier and said last-mentioned secondary winding, said second filter having two electrolytic condensers connected in parallel with said last-mentioned secondary winding, said filter being connected to said microphone for supplying current thereto. 5

2. An amplifier circuit having connected therewith a microphone operated by current means energized from an alternating current source, said operating current means comprising a source of alternating current, a single transformer having a primary winding and a plurality of secondary windings, the primary winding of said transformer connected to the alternating current source, one of the secondary windings of said transformer connected to a rectifier tube, a filter connected to said rectifier tube and said secondary winding, said filter connected to said amplifier for supplying current thereto, at least one other secondary winding of said transformer connected to a dry copper oxide rectifier, a second filter connected to said dry copper oxide rectifier and said last-mentioned secondary winding, said second filter comprising two electrolytic condensers connected in parallel with said last-mentioned secondary winding, said filter being connected to said microphone for supplying current thereto. 10

3. An amplifier circuit having connected therewith a microphone operated by current means energized from an alternating current source, said operating current means comprising a source of alternating current, a single transformer having a primary and a plurality of secondary windings, the primary winding of said transformer connected to the alternating current source, one of the secondary windings of said transformer connected to a rectifier tube, a filter connected to said rectifier tube and said secondary winding, 15

said filter connected to said amplifier for supplying current thereto, at least one other secondary winding of said transformer connected to a selenium rectifier, a second filter connected to said selenium rectifier and said last-mentioned sec- 20

ondary winding, said second filter comprising two electrolytic condensers connected in parallel with said last-mentioned secondary winding, said filter being connected to said microphone for supplying current thereto. 25

4. An amplifier circuit having connected therewith a microphone operated by current means energized from an alternating current source, said operating current means comprising a source of alternating current, a single transformer having a primary and a plurality of secondary windings, the primary winding of said transformer connected to the alternating current source, one of the secondary windings of said transformer connected to a rectifier tube, a filter connected to said rectifier tube and said secondary winding, 30

said filter connected to said amplifier for supplying current thereto, at least one other secondary winding of said transformer connected to a selenium rectifier, a second filter connected to said selenium rectifier and said last-mentioned sec- 35

ondary winding, said second filter comprising two electrolytic condensers connected in parallel with said last-mentioned secondary winding, said filter being connected to said microphone for supplying current thereto. 40

5. An amplifier circuit having connected therewith a microphone operated by current means energized from an alternating current source, said operating current means comprising a source of alternating current, a single transformer having a primary and a plurality of secondary windings, the primary winding of said transformer connected to the alternating current source, one of the secondary windings of said transformer connected to a rectifier tube, a filter connected to said rectifier tube and said secondary winding, 45

said filter connected to said amplifier for supplying current thereto, at least one other secondary winding of said transformer connected to a selenium rectifier, a second filter connected to said selenium rectifier and said last-mentioned sec- 50

ondary winding, said second filter comprising two electrolytic condensers connected in parallel with said last-mentioned secondary winding, said filter being connected to said microphone for supplying current thereto. 55

4. An amplifier circuit having connected therewith a microphone operated by current means energized from an alternating current source, said operating current means comprising a source of alternating current, a single transformer having a primary and a plurality of secondary windings, the primary winding of said transformer connected to the alternating current source, one of the secondary windings of said transformer connected to a rectifier tube, a filter connected to said rectifier tube and said secondary winding, said filter connected to said amplifier for supplying current thereto, at least one other secondary winding of said transformer connected to a rectifier, a second filter comprising electrolytic condensers, said filter connected to said rectifier and in parallel with said last-mentioned secondary winding, said second filter connected to said microphone for supplying current thereto.
5. An amplifier circuit having connected there-

with a microphone operated by current means energized from an alternating current source, said operating current means comprising a source of alternating current, a single transformer having a primary and a plurality of secondary windings, the primary winding of said transformer connected to the alternating current source, one of the secondary windings of said transformer connected to a rectifier tube, a filter connected to said rectifier tube and said secondary winding, said filter connected to said amplifier for supplying current thereto, at least one other secondary winding of said transformer connected to a rectifier, a second filter comprising two electrolytic condensers of substantially 100 microfarads each connected to said rectifier and in parallel with said last-mentioned secondary winding, said second filter connected to said microphone for supplying current thereto.

OTTO WOHLFARTH. 20
